Patented Sept. 21, 1926.

Des. 71,101

UNITED STATES PATENT OFFICE.

GIBSON CATLETT, OF CHICAGO, ILLINOIS.

DESIGN FOR A COMBINATION MOUNTING AND FRAME.

Application filed March 12, 1926. Serial No. 16,901. Term of patent 14 years.

To all whom it may concern:

Be it known that I, GIBSON CATLETT, a citizen of the United States, residing at Chicago, in the county of Cook and State of Illinois, have invented a new, original, and ornamental Design for Combination Mounting and Frame, of which the following is a specification, reference being had to the accompanying drawing, forming part thereof.

The figure of the drawing is a perspective

view of a combination mounting and frame showing my new design. The vertically and obliquely lined portions in the drawing represent portions of two different colors contrasting with the unlined portions thereof.

I claim:

The ornamental design for a combination mounting and frame as shown and described.

GIBSON CATLETT.
